(57) **CLAIM**

The ornamental design for a step stool, as shown and described.

DESCRIPTION

FIG. 1 is a perspective view of a first embodiment of the step stool;

FIG. 2 is a front view of the step stool depicted in FIG. 1; FIG. 3 is a rear view of the step stool depicted in FIG. 1; FIG. 4 is a right side view of the step stool depicted in FIG. 1;

FIG. 5 is a left side view of the step stool depicted in FIG. 1;

FIG. 6 is a top view of the step stool depicted in FIG. 1; and, FIG. 7 is a bottom view of the step stool depicted in FIG. 1. The broken lines in the drawings illustrate portions of the step stool and form no part of the claimed design.
